GAS BURNER

Theophilus Symmonds, Buffalo, N. Y.

Application April 20, 1938, Serial No. 203,119

7 Claims. (Cl. 158—116)

This invention relates to gas burners of the type used in heating apparatus, such as stoves, furnaces, and the like.

One of the objects of my invention is to provide a gas burner of the type mentioned, wherein the construction thereof prevents the formation of carbon, so that a perfectly blue white-tipped flame is assured at all times.

Another object of my invention is to provide a burner in which the mixture of air and gas fed thereto is subjected to continual movement therein during the process of consuming the gas so that a more efficient mixture is assured at the point or points of ignition.

Another object of my invention is to provide a gas chamber within the burner, a portion at least of which is above the plane of ignition of the gas escaping from the burner.

Another object of my invention is to provide a burner which is economical in gas consumption and in which the proper proportion of gas and air to form the combustible mixture is maintained at all times without the need of regulating the supply of either the gas or air.

Still another object is to provide a baffle above the flame or flames of the burner against which they play to cause said baffle to become red-hot and thereby consume any products of combustion not fully consumed beneath the baffle; said baffle, by preference, having numerous openings therethrough so that the flames may also pass through the baffle and rise above the latter; the construction being such that the unconsumed products beneath said baffle become ignited by contact with said baffle and issue in flames above the baffle.

A further object of my invention is to provide a comparatively large mixture chamber having a portion extending above the plane of ignition of the mixture and in which portion the mixture is caused to expand from the effects of the heat transferred to the burner above the plane of ignition.

A further object of my invention is to provide a gas burner with a pressure equalizing chamber into which air and gas are passed and wherein the air and gas constituents of the mixture thoroughly commingle so as to assure a combustible mixture of maximum efficiency at the point or points of ignition; the said pressure equalizing chamber being formed to cause the combustible mixture to travel in a circuitous manner from the point of entrance of the constituent parts thereof into the chamber to the point or points of ignition thereof.

A still further and very important object of my invention is to provide a gas burner in which the gas and air admission openings are so proportioned that regulation under adjustment of an air mixer is found unnecessary when such mixer is associated with the pressure equalizing chamber of my improved burner.

A still further object is to provide a gas burner with a mixture chamber so constructed that upon shutting off the supply of gas thereto, the flame or flames of the ignited mixture will gradually diminish in size until completely extinguished without the usual popping noise or without possibility of the mixture becoming ignited in the air mixer of the burner.

With the above and other objects in view, my invention consists in a gas burner having the above mentioned and other advantages; and also in the novel features of construction and in the arrangement and combination of parts to be hereinafter described and more particularly pointed out in the subjoined claims.

In the drawings,

Fig. 1 is a transverse section of a gas burner embodying my invention, it being of the type adapted for use in a gas-burning stove or heater.

Fig. 2 is a front elevation of the gas burner.

Fig. 3 is a longitudinal section taken on line 3—3, Fig. 1.

Fig. 4 is a transverse section through a portion of the gas burner taken on line 4—4, Fig. 3, looking in the direction of the arrow crossing said line.

Fig. 5 is a top plan view of the main or inner portion of the gas burner.

Fig. 6 is a perspective view of a portion of the upper part of the main portion of the gas burner with the baffle removed therefrom.

Fig. 7 is a detached perspective view of the baffle.

Fig. 8 is a longitudinal section through the air mixer and adjacent portions of the pipes connected therewith.

Fig. 9 is a cross section taken on line 9—9, Fig. 8.

Fig. 10 is a central vertical section through a gas burner of modified formation, one particularly adapted for use in furnaces and like heating apparatus.

Fig. 11 is a cross section taken on line 11—11, Fig. 10.

Having reference to Figs. 1 to 9, 12 designates the main or body portion of the burner which is preferably cast to form and made hollow so as to provide what I term a pressure-equalizing

15

25

30

35

40

45

55

mixture chamber designated by the numeral 13. In preferred form this body portion has a front wall 14 formed in two sections, 14^a and 14^b which are connected together by a horizontal 5 wall 15, a rear wall 16, a bottom wall 17, and a rounded top wall 18. By forming the front wall of the mixture chamber in two sections and connecting them by the horizontal or what I term a flame wall 15, said front wall has offset sections; the upper section 14^a thereof and the rear wall 16 merging to form the rounded top wall 18. The upper portion of the mixture chamber is therefore diminished in depth; and that portion thereof so diminished or reduced in size I utilize 10 as an expansion chamber and designate by the numeral 19.

Threaded into the bottom wall 17 is a mixture admission pipe 20, onto the lower end of which is threaded an air mixer 21. This air mixer has 20 an upwardly or inwardly tapering body portion 22 terminating at its upper or inner end in a nipple 23 into which said pipe 20 is threaded, and its enlarged or outer end is equipped with an axial inwardly-extending cone 24 connected 25 to the peripheral wall of the air mixer by diametrically disposed arms 25.

The axial inwardly-extending cone and said arms 25 form a spider-like structure within said mixer of which the said cone is the center. This 30 cone is slightly truncated and made hollow to receive a gas supply pipe 26, and in the truncated end of this hollow cone a comparatively small gas inlet-opening 27 is formed, it being preferably an opening formed with a forty-seven 35 drill, as compared to the air-inlet of the mixer of approximately two square inches.

In the horizontal or flame wall 15 of the gas burner proper or body portion 12, mixture escape openings or outlets 28 are formed. These are 40 closely spaced and direct the flames, when the mixture issuing therefrom is ignited, in an upward direction. The horizontal plane in which these mixture escape openings or outlets are arranged determines the lower limit of the expansion 45 chamber 19. Whether or not diminished in size, all that portion of the chamber 13 above this plane, which I also term the plane or region of ignition, is considered the expansion chamber, due to the fact that such portion is subjected 50 to heat of the burning mixture. This causes the gas within the expansion chamber to be pre-heated, and under pressure of the entering mixture find its way to the plane of ignition, where it escapes through the openings or outlets 28 and results in perfectly blue flames with white 55 tips; thus guarding against the formation of carbon and assuring greatest heat efficiency.

Along the upper section 14^a of the front wall, a horizontal supporting ledge 29 is formed, and 60 in a plane at which said upper section meets the rounded upper wall 18, an upstanding flange 30 is formed. Recesses 31 are formed exteriorly 65 in the body portion or burner proper 12 at opposite ends; and spaced from the rear and bottom walls of these recesses are anchor bars 32 for a purpose to presently appear.

33 designates a baffle which has its main portion of channel formation, and rising from the upper side thereof along the greater part of its 70 rear marginal portion is a hook-shaped flange 34. Spaced from opposite ends of said flange 34 and extending rearwardly from the body portion of the baffle are hooks 35. The rear wall or flange 36 of this channel-shaped baffle bears 75 against the front wall of the upper section 14^a

of the chamber 13, and the lower edge thereof receives support from the ledge 29. The front wall or flange 37 of said baffle is slightly wider than the rear wall or flange 36 so that it extends 5 below the plane at which the rear wall or flange receives support from the ledge 29; thus more effectively confining the flames to a region where the transfer of heat therefrom will be most efficient. The connecting web 38 of this channel-shaped body portion is provided with numerous 10 openings 39, somewhat larger than the openings 28 in the burner proper.

When this baffle is in position it not only receives support from the ledge 29, but the hook-shaped flange 34 is hooked over the upstanding 15 flange 30 on the burner and the hooks 35 at opposite ends of the baffle are hooked onto the anchor bars 32. Thus the baffle is supported in a secure manner and the flames issuing from the openings or outlets 28 rise upwardly and play 20 against the inner surfaces of said baffle, and when a full supply of gas is furnished, the burner and the mixture therein is maintained under constant pressure, the flames of the burner also pass up through the openings 39 in the baffle. 25 Should any unconsumed products of combustion reach the baffle, they will become ignited by the latter owing to its red-hot condition which will be maintained after the flames have properly heated the same.

I desire to state at this time that the mixture escape openings or outlets 28 are quite numerous, as will be seen from the number of nipples 40 shown rising from the horizontal or flame wall 15. These openings are formed through 35 these nipples and are approximately one-sixteenth of an inch in diameter, their aggregate area being such that the size of the mixture admission pipe 20 will furnish sufficient gas mixture to the interior of the burner to allow the 40 building up of pressure in the pressure-equalizing mixture chamber 13 so that the flames issuing from the escape openings 28 are constant and do not vary in size.

The gas mixture entering the chamber 13 is, 45 by reason of the small escape openings 28, practically maintained at a pressure governed by the pressure behind the gas supply, and it rises to the top of the chamber where it is pre-heated and caused to expand by transfer of the heat 50 from the wall of the expansion chamber, which is heated by contact of the baffle 33 therewith and the effect of the flames issuing from the escape openings 28. This pre-heated gas is drawn upon as required at the escape openings 55 28, and by reason of the fact that the gas mixture is in constant motion within the pressure-equalizing mixture chamber 13, a thorough 60 commingling of the constituent parts in this mixture is assured to effect, as near as possible, a perfect combustible mixture.

By providing the burner with a pressure-equalizing mixture chamber and causing constant motion of the mixture within the chamber under pressure of the inflowing mixture and 65 the consumption of the mixture furnished at the ignition points, a perfectly blue and hot flame is assured. These flames and the heat therefrom are trapped or confined within the baffle 33 by the parallel walls or flanges 36 and 70 37, and the foraminous top wall 38, with the result that this baffle becomes red hot; and should any unconsumed products of combustion escape from the flames, they will be brought into contact with the red hot baffle and be fully con- 75

sumed thereby. The flames may issue through the perforations or openings in the baffle and any products of combustion escaping through these perforations or openings become ignited and result in the formation of flames above the baffle. It will be apparent that by reason of the construction shown, the heat of the baffle, to the extent mentioned, will cause the upper portion of the burner to become well heated, with the result that the portion of the gas-mixture within the expansion chamber 19 will become preheated, and that both the baffle and the burner casing radiate heat, as well as the flames directly.

Incorporated in my improved burner is an outer casing or heat circulator 41 which almost entirely surrounds the burner proper. It conforms in shape somewhat to that of the exterior of the burner proper and therefore has a front wall 42 whose upper end terminates substantially in the ignition plane of the burner, a bottom wall 43 into which said front wall merges, a rear wall 44, and a rounded top wall 45 into which said rear wall merges. These walls are separated from the burner proper by an intervening space 46. A portion of the front of this outer casing or heat circulator is open, as at 47, the opening extending the full width thereof, and in height rising from approximately the plane or region of ignition to the upper side of the baffle so that the major portion of the heat from the flame and baffles may escape through said opening.

Due to the fact that the flames may at times rise above the baffle, this outer casing becomes well heated and the heated air within the intervening space 46, which may be referred to as a hot-air circulation passage, travels downwardly in rear of the burner proper, thence forwardly underneath the latter, and finally upward so as to impinge against the flames of the burner, thereby supplying heated air which aids materially in the combustion of the gas mixture.

This outer casing or heat circulator also has end walls 48 which close the opposite ends of the hot-air circulation passage 46; and in order to secure the same in place, securing lugs 49 are cast on the burner proper at opposite ends thereof; securing screws 50 being passed through the end walls 48 and threaded into said securing lugs. This outer casing or heat circulator may, however, be secured in place in any other approved manner.

In the modification of my invention illustrated in Figs. 10 and 11, all the essential features of the burner illustrated in the preceding figures of the drawings are retained, but the burner differs in formation of the parts. In these figures the mixture admission pipe is also designated by the numeral 26; the main or body portion of the burner by the numeral 12^a, into the lower end of which said mixture admission pipe is threaded. The main or body portion is cylindrical in cross section and the upper portion thereof reduced in diameter to form the expansion chamber 19^a. The lower portion of this burner is therefore of larger diameter than the upper portion or expansion chamber 19^a, and these two portions together serve as the pressure equalizing mixture chamber, designated 13^a.

By reducing the diameter of the upper portion of the body portion, a horizontal or shoulder wall 15^a is provided which corresponds with the shoulder wall 15 in the preceding figures, and like the latter it is provided with mixture escape open-

ings or outlets, which I designate 28^a in this instance.

The baffle, designated 33^a, is in the form of a cap having a reduced upper end 51 open at the top, as at 52, to form an inwardly-extending supporting flange 53. The reduced upper portion of this cap-like baffle is of a size to easily receive the upper end of the main or body portion of the burner, and the lower portion is of a diameter somewhat greater than the lower portion of said body portion so that the flames issuing from the mixture escape openings or outlets 28^a are trapped or confined within this baffle. By reducing the upper end of this cap-like baffle a shoulder wall 54 is provided from 15 which depends a cylindrical confining wall 55 serving the same purpose as the parallel depending walls or flanges 36 and 37 of the baffle shown in the preceding figures. The shoulder wall 54 acts in the same manner as the top wall 20 38 of the baffle shown in the preceding figures, and it has openings 39^a therein.

It will be apparent that in this modified form of my invention the flames play against the shoulder wall 54 of the baffle, which may also 25 be termed the top wall to conform to the term applied to the wall 38 in the preceding figures, and thoroughly heat this top wall and the depending cylindrical flange 53, with the result that the upper portion of the expansion chamber 19^a becomes heated. The action of the mixture in this instance is quite similar to that taking place in the burner illustrated in the preceding figures, or what may be termed the preferred construction of burner, and all the 30 advantages of the preferred construction are retained. If desired, this construction may also have a heat circulator applied thereto, but this is not generally considered necessary for burners 35 installed in boilers or furnaces.

It will be apparent from the foregoing that this burner is very economical in that the inlet orifice for the gas is exceedingly small, yet provides sufficient gas, when properly mixed with air and treated as my improved burner provides, 45 to furnish a mixture for the large number of mixture escape openings or outlets while assuring a perfectly blue flame with practically no unconsumed gases escaping therefrom, to meet any given requirement. Therefore my improved 50 burner will furnish heat with a gas consumption much less than has heretofore been possible.

Having thus described my invention, what I claim is:

1. A gas burner having a hollow body portion 55 provided with an upwardly facing wall portion, said wall portion having mixture escape openings therein, and a baffle disposed above said upwardly facing wall portion and having openings therein through which the flames issuing 60 from said mixture escape openings may pass, said baffle having a depending confining wall terminating at its lower end in spaced relation to said upwardly facing wall.

2. A gas burner, comprising a body portion 65 having a pressure equalizing chamber restricted at its upper end to form a mixture expansion chamber, said body portion having a horizontal wall portion formed by restricting the upper end of said pressure equalizing chamber, a mixture 70 inlet for said pressure equalizing chamber, said horizontal wall portion having a series of mixture escape openings, an upwardly extending flange on said body portion, and a baffle having a hook-shaped flange engaging said upwardly 75

extending flange, said baffle being situated over said horizontal wall portion and against which the flames of the burner play.

3. A gas burner, comprising a body portion having a pressure equalizing chamber restricted at its upper end to form a mixture expansion chamber, said body portion having a horizontal wall portion formed by restricting the upper end of said pressure equalizing chamber, a mixture inlet for said pressure equalizing chamber, said horizontal wall portion having a series of mixture escape openings, an upwardly extending flange on said body portion and a forwardly extending ledge in a plane beneath said flange, and a baffle having a hook portion engaging said upwardly extending flange and a depending wall resting on said forwardly extending ledge, said baffle having openings therethrough and being situated above said horizontal wall portion.
- 20 4. A gas burner, comprising a body portion having a pressure equalizing chamber restricted at its upper end to form a mixture expansion chamber, said body portion having a horizontal wall portion formed by restricting the upper end of said pressure equalizing chamber, a mixture inlet for said pressure equalizing chamber, said horizontal wall portion having a series of mixture escape openings, said body portion having recesses at its upper end and anchor bars in said recesses, and a baffle situated over said horizontal wall portion and having hooks engaging said anchor bars.
- 35 5. A gas burner, comprising a body portion having a pressure equalizing chamber restricted at its upper end to form a mixture expansion chamber, said body portion having a horizontal wall portion formed by restricting the upper end of said pressure equalizing chamber, a mixture inlet for said pressure equalizing chamber, said hor-

izontal wall portion having a series of mixture escape openings and said body portion having a horizontal supporting ledge near its upper end and recesses at its upper end provided with anchor bars extending through said recesses, and a baffle having a horizontal wall, an inner depending wall and an outer depending wall and being provided with hooks engaging said anchor bars, the inner of said depending walls resting upon said horizontal supporting ledge.

6. A gas burner, comprising a hollow body portion restricted at its upper end to provide an upwardly facing wall portion between the upper and lower ends of said body portion, said wall portion having a plurality of mixture escape openings serving to direct flames upwardly when the mixture escaping through said escape openings is ignited, and a baffle spaced from and supported above said upwardly facing wall portion and having a depending wall along its outer edge to confine the flames from the burner between said depending wall portion and the restricted upper end of said body portion and to cause said flames to heat said baffle and the restricted upper end of said body portion.

7. A gas burner, comprising a hollow body portion restricted at its upper end to provide an upwardly facing wall portion between the upper and lower ends of said body portion, said wall portion having a plurality of mixture escape openings serving to direct flames upwardly therefrom when the mixture escaping through said escape openings is ignited, and a baffle supported by the restricted upper part of said hollow body portion and overhanging said upwardly facing wall, said baffle having openings therein and a depending wall spaced from the restricted upper end of said body portion.

THEOPHILUS SYMMONDS.
